UNITED STATES PATENT OFFICE.

ARTHUR M. EICHORN, OF NEW YORK, N. Y., ASSIGNOR TO EVERNU RUBBER HEEL CORPORATION, OF NEW YORK, N. Y., A CORPORATION OF DELAWARE.

ADJUSTABLE RUBBER HEEL.

Application filed April 29, 1925. Serial No. 26,628.

This invention relates to resilient heels for boots and shoes and has particular reference to that type of devices commonly known as rotary heels, providing for such adjustment or interchangeability as to insure maximum length of wear for the heels together with a uniformly neat appearance, as well as safety with respect to the wearer's ankles.

10 This invention constitutes an improvement over the subject matter of my co-pending application for resilient shoe heels, filed February 20th, 1924, Serial No. 694,003, and the present specification constitutes a disclosure of means to render it impossible for the adjustable or renewable tip to be separated accidentally or unintentionally from the base or fixed portion of the structure.

Another object of the invention is to provide a cushioned heel tip of molded rubber or its equivalent within which is molded a headed pin for interlocking co-operation with the fixed part of the heel, the molding of the tip being so performed as to provide 25 superior cushioning qualities as well as to insure against accidental separation of the parts.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

40 Figure 1 is a bottom plan view of one of my improved heels in assembled position.

Fig. 2 is a plan view of the tip shown herein in the form of a disk.

Fig. 3 is a vertical longitudinal section on the line 3—3 of Fig. 1.

45 Fig. 4 is a view corresponding to Fig. 1 but with the tip removed.

Fig. 5 is a detail perspective view of the headed pin molded in the tip, but on a scale reduced from that in Fig. 3.

50 Fig. 6 is a plan view of the anchor plate molded in the base, and on a similar scale to that of Figs. 3 and 4.

Figs. 7 and 8 are detail diagrams indicating the correlation between the plate and headed pin, Fig. 7 showing the oblique po-

sition of these parts when being assembled or disassembled, and Fig. 8 showing the normal interlocking position.

Fig. 9 is a diagram indicating approximately the position of the tip while sliding 60 into interlocking position with respect to the base.

Fig. 10 is a diagram indicating approximately the manipulation of the disk or tip for normal rotary adjustment, the headed 65 pin remaining in normal interlocking position.

Fig. 11 is a detail view showing a slight variation in form of the anchor plate and stop lip.

Referring now more particularly to the drawings, the invention will be understood as comprising two main parts,—the base 11 and the tip 12. The base may be made of any suitable material, preferably molded 75 rubber, for best cushioning effect and uniformity of appearance, agreeable to the now common rubber heel usage. It is formed to correspond to the usual heel design and comprises a tread portion 13 adjacent to the 80 breast 14 of the heel and formed with an arc shaped shoulder 15 at the rear of the breast. At the center of the curvature of the shoulder the base is formed with a hole or clear opening, the center of which is 85 concentric with the normal rear curvature of the heel.

Secured in any suitable manner to and carried by the base is an anchor plate 16 made preferably of sheet metal and preferably molded within the body of the base. At the center of the plate is formed a key-hole slot 17 and at the smaller end thereof there is formed a bearing seat 18 concentric with the heel curvature aforesaid and also 90 concentric with the hole through the base. At the other end of the slot is formed a lip 19 constituting a stop. This lip may be constructed in any suitable manner, but as shown in Figs. 3 and 8, it is deflected from 95 the plane of the plate. The plate is provided also with a series of nail holes 20, the metal surrounding them being depressed in the direction in which the lip 19 is deflected so as to bring the bottoms of the depressions relatively close to the surface of the sole against which the base is fastened, and also to provide counter sunk seats for the fastener heads indicated in dotted lines 100 at 21 in Fig. 3. The plate is provided also 105 at 21 in Fig. 3. The plate is provided also 110

with numerous large holes 22 through which the plastic material passes readily during the formation of the structure in the molds. It will thus be seen from Fig. 3 that the plate is embedded within the body of the base and except at the open center is practically invisible even when the tip is removed.

The tip 12 may be of any suitable material, construction, or form, but preferably is of circular or disk shape molded to be slightly convex on the outer or tread surface 12^a and concave on its inner surface 12^b and of the same diameter as the curved shoulder portion 15 of the base into and against which it fits normally for use. While the thickness or depth of the disk is substantially equal to that of the shoulder, the convexity of the disk provides a slight extension of the central portion thereof beyond the plane of the tread 13 of the base.

Centrally of the tip is carried, as by molding therein, a pin 23 having an external head 24 and an internal anchorage plate or disk 25. This disk 25 is formed preferably with holes 26 through which the plastic rubber is forced during the molding action, making thereby a stronger union between the rubber and metal parts. Surrounding the pin on the surface 12^b of the disk is formed an annular depression 27 which adds resiliency to the tip and facilitates the connection or disconnection thereof with respect to the base. At 28 I show a collar of rubber surrounding the pin between the pin and the depression 27 which is formed coincident with the molding operation at which time it fills completely the space between the disk 25 and the head 24. By the application, however, of a tool during the manufacturing operation the end of the collar is sheared off adjacent to the head, leaving a clearance at 29 to receive the portion of the plate immediately surrounding the seat 18. This collar 28 of rubber constitutes a cushion giving added resiliency to the tip and serves normally to hold the head of the pin flat against the seat portion of the plate subject of course to the depression of the head into the clear space 30 surrounding the plate slot as an incident of the wearer's weight coming upon the heel.

For convenience of manufacture and manipulation of the device, the head 24 is preferably circular and the diameter of it approximates the total width of the slot 17 as indicated by dotted lines in Fig. 4, but the diameter is preferably greater than the clear space between the lip or stop 19 and the rim of the seat 18. In other words, in the normal position, substantially as shown in Figs. 3 and 8, one side of the head overlaps the seat 18, while the other side thereof lies in close or abutting relation to the stop 19. It follows, therefore, that while the

head may be connectible or disconnectible with respect to the plate by slipping edge-wise through the slot 17 while lying in a plane oblique to the plane of the plate, by no possibility can the head be disconnected from the plate while in the normal plane parallel to the plate. Furthermore, the seat 18 prevents lateral movement of the pin in any direction except toward the lip or stop 19, and hence so long as the head is maintained parallel to the plate it can be moved forward in the direction of the stop only to abut against it or ride firmer behind it. That is to say, if, while the tip is under flattening compression, the tip and pin be forced forward, the edge of the head would take the direction of the arrow *b* in Fig. 8, thereby making more positive the interlock between the parts. The edge of the stop is cut or stamped preferably square or at right angles to the adjacent metal of the stop forming an incline as a result of the bending of the stop as shown, whereby the tendency of the head to interlock more firmly under the stop is increased.

The base adjacent to the tip is provided with one or more lugs 31 extending into selected holes or pits 32 formed in the inner face 12^b of the tip concentric with the pin. Any suitable number of pits may be formed, but by providing eight as shown a substantially uniform wear on the point portion of the tip is assured so that by adjusting the tip around the axis of the pin from time to time by springing it out from the lugs as shown in Fig. 10, and giving it a partial rotation, the heel always presents a neat flat appearance and the best results to the wearer are effected.

After the base is nailed or otherwise secured to the shoe sole as usual as by the application of nails 21 through the holes 20^a and 20^b, the holes 20^a registering with the plate holes 20, the tip is inserted as suggested in Figs. 7 and 9, the body of the tip being reversely flexed so that the lugs 31 will not interfere, and the forward side of the tip will pass into place over the shoulder 15, the head of the pin at this time being in a plane oblique to the plane of the plate so as to pass edge-wise through the slot 17. The pin at this time comes into or against the seat 18, while the forward edge of the disk comes into abutting position against the shoulder 15, the disk then being adjusted rotarily to make the lugs 31 register with two of the pits 32, the connection is complete and secure and ready for use. After a portion of the point of the tip is worn off as indicated at 12^c, Fig. 10, the adjacent portion of the tip is sprung out and the tip is rotated through a suitable angle to bring the lugs into other of the pits when the structure constitutes practically a renewed heel. Thus as shown eight adjust-

ments may be effected without removal of the tip for the application of a new one. The base is practically indestructible and new tips may be substituted as often as used 5 ones are worn out.

In Fig. 11 I show a slight variation in anchor plate 16^a in which the lip 19^a is deflected to a less degree from the plane of the plate than in Figs. 7 and 8, and the 10 points or shoulders 18^a of the seat 18 are bent in the opposite direction slightly. The clearance afforded for the head 24 therefore is practically the same as already described and the same interlocking effect is realized.

15 I claim:

1. A rubber heel comprising, in combination, a base, a tip, and means for disconnectably attaching the tip to the base, said means including a plate carried by one of the parts 20 aforesaid and a headed member carried by the other, the plate having an opening to receive the head when the part carrying it is slipped therealong with the head at an oblique angle to the plate, and the plate 25 having stop means to limit and prevent sliding movement in any direction of the headed member in a plane parallel to the plate.

2. In a rubber heel, the combination of a base, an anchor plate carried thereby, a tip 30 for detachable connection with the base, and an engagement member carried by the tip, the plate and the engagement member being provided with correlated devices to effect connection while the tip and base are moved 35 relatively to each other along oblique planes and are interlocked positively from separation when moved relatively along parallel planes.

3. In a rubber heel, the combination of a 40 base to be fixed to the shoe, a tip for detachable connection with the base, and interlocking plate and headed members carried by the first two parts, the plate having a key-hole slot through which the head of the 45 headed member may pass when at an oblique angle with respect to the plate, the head in interlocked position lying in a plane parallel to the plate, and the plate having a stop adjacent to the slot, said stop lying in the 50 normal plane of the head and serving to prevent unintentional movement of the head from interlocking position.

4. In a rubber heel, the combination with a base for permanent connection with a shoe 55 and an anchor plate carried thereby, the plate having a key-hole slot having at one end a bearing seat and at the other end a rigid stop, of a tip for adjustable detachable connection with the base, and a headed 60 member carried by the tip, the head thereof

being projectable through the slot past the stop, while inclined with respect to the plate, and into normal interlocking seated position in said seat parallel to the plate, said stop serving positively to prevent accidental 65 movement of the head along its normal plane.

5. In a heel, a base, an anchor plate carried by the base and having a slot forming a bearing seat, a rubber tip, and a headed 70 pin molded in the tip, the head of the pin being projectable through the slot into interlocking bearing position in said seat, a portion of the tip rubber forming a collar surrounding the pin and constituting a resilient 75 cushion, for the purposes set forth.

6. A structure as set forth in claim 5 in which the collar cushion bears normally against one side of the plate, serving to hold the pin head against the opposite side of the 80 plate, and the plate carries a stop close to the head in the normal plane thereof to prevent accidental movement of the pin from its seat.

7. In a resilient heel, the combination of 85 a base for permanent attachment to a shoe and having a seat adjacent to its tread, an anchor member secured in the base in communication with said seat, a resilient tip member fitted in said seat and adapted to receive the impact with the pavement, and a pin carried by the tip member remote from its periphery and adapted to interlock with said anchor member for holding the tip member detachably in said seat, the surface 90 of the tip member remote from its tread surface being provided with a pit surrounding the pin and the interlocking of the pin with the anchor member being effected as a result 95 of inward distortion of the portion of the tip member carrying the pin and as a result of said pit formation.

8. In a resilient heel, the combination of 100 a base having an arc-shaped seat, an anchor member fitted in the base at the center of curvature of the seat, a disk-shaped resilient tip fitted in said seat and rotatable therein, a projection carried by one of said parts while the other of said parts is provided with a series of pits concentric with the 105 axis of rotation and adapted to receive selectively said projection, and a metallic pin fitted in the central portion of the tip and having on its inner end a head for positive interlock in said anchor member coincident 110 with the operation of said projection.

115 In testimony whereof I affix my signature.

ARTHUR M. EICHORN.
